UNITED STATES PATENT OFFICE.

FREDERICK E. COWELL, OF COPPER CITY, BRITISH COLUMBIA, CANADA.

SAW-SET.

1,055,712.

Specification of Letters Patent. Patented Mar. 11, 1913.

Application filed June 29, 1912. Serial No. 703,739.

To all whom it may concern:

Be it known that I, FREDERICK E. COWELL, a citizen of the United States, residing at Copper City, Province of British Columbia, 5 Canada, have invented certain new and useful Improvements in Saw-Sets, of which the following is a specification.

This invention relates to hand operated saw sets, and has for its object the provision of a tool of simple construction which may be operated without fatigue to efficiently set the teeth of a saw at any desired angle.

The invention, also, has for its object the provision of novel means for supporting and adjusting the anvil, and seeks, generally, to improve the construction and operation of a saw set to the end that the efficiency and durability of the same may be increased.

The invention is illustrated in the accompanying drawings and will be hereinafter fully described, the novel features being subsequently pointed out in the claims following the description.

In the drawings: Figure 1 is a sectional elevation of a saw set embodying my invention; Fig. 2 is a sectional view on the line 2-2 of Fig. 1; Fig. 3 is a detail front elevation of the anvil; Fig. 4 is a detail perspective view of the anvil adjusting device.

In carrying out my invention, I employ a body 1 which may be cast in one integral piece and consists of a substantially cylindrical main portion having a handle 2 extending downwardly from its rear end and is provided at its front end with a depending saw supporting and bracing head 3. A lug or bracket 4 depends from the main portion of the body 1, and a set screw 5 is mounted in the said lug or bracket to bear against the saw blade, indicated at 6, and clamp the same firmly against the head 3 so as to support the same in proper position between the die and the anvil.

Within the main portion of the body 1 is a longitudinal chamber 7 opening at its front end above and in advance of the lug or bracket 4 and opening at its rear end through the under side of the body. Within said chamber 7 are transverse webs or partitions 8 which form supports for the die or hammer 9, said die, hammer, or setting pin being normally held retracted within the chamber by a spring 10 coiled around the pin and bearing against the front web

or partition 8 and against a stop 11 in the pin, as clearly shown. The stop 11 is conveniently a small pin inserted through the setting pin or die, and to provide a wider support for the end of the spring, a washer 12 may be fitted around the die against the said stop. The front end of the die or setting pin is beveled to engage the saw teeth, and the rear end thereof is beveled to bear against the upper end of an operating lever 13 fulcrumed at 14 within the chamber 7 at the lower rear end thereof. The upper end of the lever 13 is provided with an inclined working face 15 which rests 70 against the inner or rear end of the die so as to permit an easy sliding relative movement of the parts in the operation of the device.

The saw supporting and bracing head 3 is provided, near its upper end, with a vertical slot 16 through which passes a screw 17 carrying at its inner end an anvil 18. The said anvil consists of a block having a plurality of faces 19 which are beveled outwardly from approximately the center of 80 the anvil to the edge thereof at different angles, so that, by properly adjusting the anvil, a face corresponding to the angle to be given the saw tooth may be brought in co-operative relation to the die. The bolt 85 or screw 17 is provided with a thumb nut 20 on its outer end which may be turned home against the head 3 to thereby clamp the anvil in its adjusted position. The anvil may be raised or lowered so as to give the 90 saw a coarser or finer set by means of the regulating device 21 consisting of a disk or plate 22 having a central opening to fit around the screw 17 between the head 3 and the anvil and a supporting lip or wing 23 95 connected with the edge of said disk or plate and adapted to project over the upper edge of the head 3. The edge of the head is provided, immediately adjacent its center, with the oppositely extending bevel surfaces 24, 100 25, which extend in opposite directions from the central vertical line of the head and are disposed at different angles. When the lip 23 rests in the angle formed by the surfaces 24, 25, the screw or bolt 17 will be at the lower end of the slot 16, and the anvil will consequently be in its lowest position so that the coarsest set will be given the saw. If the lip be turned so as to ride up the surface 24, the screw or bolt 17 will be brought 105 to the center of the slot 16, while, if the lip be caused to ride up the surface 25 to the

110

upper end thereof the screw or bolt 17 will be raised to the upper end of the slot 16. In this simple manner, I provide for adjusting the anvil so as to permit the saw 5 being given a coarse or fine set, as may be desired.

The operation of the device is thought to be clear from the foregoing description. The tool is engaged over the edge of the 10 saw, as indicated in Fig. 1, and the thumb screw 5 is turned home against the saw blade so as to hold it firmly against the head 3. The anvil, having been previously adjusted to bring the proper face into the operative 15 position, the lever 13 is drawn toward the handle 2 by the fingers of the operator, and this movement of the lever will project the die or setting pin 9 against the tension of the spring 10, thereby forcing the tooth 20 which is in the path of the pin against the anvil and giving the same the desired set. Upon the lever 13 being released, the spring 10 will at once expand and return the parts to the initial position. While the thumb 25 screw 5 should be turned home sufficiently to firmly support the saw while the tooth is being set, it should be so adjusted so to permit the saw being slipped through the tool so as to bring another tooth into position to be set without requiring manipulation of the screw each time a tooth is set. The adjustment of the anvil is very quickly 30 accomplished, and when the anvil has been adjusted, it will be securely held so that it will not be dislodged during the operation of the tool. The rotation of the anvil brings any desired face thereof in operative relation

to the setting pin so that the tooth may be set at any angle while the vertical adjustment of the anvil permits the device to accommodate saw teeth of any depth.

What I claim is:

1. A saw set comprising a body having a saw supporting and bracing head depending from its front end and provided with a 45 vertical slot, an anvil, a member projecting from the said anvil through the said slot, and an anvil support engaging said member and resting upon the head and adapted to adjust the anvil vertically. 50

2. In a saw set, the combination of a body having a head at its front end provided with a vertical slot, an anvil disposed adjacent the said head, a pivot for said anvil extending through said slot and adapted to 55 rotatably adjust the anvil, means for securing said pivot in the position to which it may be rotated, and an anvil support engaging said pivot and resting upon the head.

3. A saw set comprising a body, a head at 60 its front end provided with a vertical slot, an anvil, a pivot for the anvil projecting through said slot, and a support for the anvil engaging said pivot and provided with a lip overhanging the head, the head being 65 provided with diverging beveled surfaces of different degrees of inclination to be engaged by said lip.

In testimony whereof I affix my signature in presence of two witnesses.

FRED. E. COWELL. [L. s.]
